(57) CLAIM

The ornamental design for a pendant, as shown and described.

DESCRIPTION

1. Pendant
- 1.1 : Perspective
- 1.2 : Front
- 1.3 : Top
- 1.4 : Bottom
- 1.5 : Right
- 1.6 : Left

The broken lines shown illustrate portions of the pendant and form no part of the claimed design. The back view is omitted because it is a mirror image of the front view.
